UNITED STATES PATENT OFFICE

EMIL J. BERGER, OF HATFIELD, PENNSYLVANIA, ASSIGNOR TO DEXDALE HOSIERY
MILLS, OF LANSDALE, PENNSYLVANIA, A CORPORATION OF PENNSYLVANIA

DESIGN FOR HOSIERY

Application filed May 11, 1929. Serial No. 31,175. Term of patent 7 years.

To all whom it may concern:

Be it known that I, EMIL J. BERGER, a citizen of the United States, residing at Hatfield, in the county of Montgomery and State of Pennsylvania, have invented a new, original, and ornamental Design for Hosiery, of which the following is a specification, reference being had to the accompanying drawings, forming part thereof.

In the drawings:

Fig. I is a side elevation of a stocking showing my new design; and

Fig. II is a rear elevation of the heel and ankle portion of the stocking shown in Fig. 1.

I claim:

The ornamental design for hosiery, as shown.

EMIL J. BERGER.
